UNITED STATES PATENT OFFICE

GEORGE J. FRANCOEUR, OF KANKAKEE, ILLINOIS

FIRE-ALARM SWITCH

Application filed March 22, 1929. Serial No. 349,119.

This invention relates broadly to an improved electric circuit make and break device and it has more particular reference to a structure which may be conveniently and 5 specifically defined as an electric fire alarm switch.

In carrying out the invention, I have developed an unusually simplified organization of parts for normally maintaining the 10 signal circuit open but which comes into play immediately in case of fire to close the circuit and to sound or give a signal to the occupants of a dwelling or to passers-by.

The particular details and their relative 15 arrangement and association will become more readily apparent from the following description and drawings.

In the drawings:

Figure 1 is a view in section and elevation 20 showing a switch or circuit closer constructed in accordance with the present invention, the device being suspended in a vertical position for operation.

Figure 2 is a bottom plan view of Figure 25 1.

Figure 3 is a horizontal sectional view, taken approximately upon the plane of the line 3—3 of Figure 1.

Figure 4 is a side view with a portion 30 broken away showing the manner in which the same device may be hung or placed in a horizontal operating position.

Figure 5 is a view showing how it may be employed in an inverted vertical position.

Figure 6 is a detail view of a contact plate.

The entire structure may be well seen in Figure 1, wherein it will be observed that 40 the reference character 7 designates generally a casing or housing comprising a cap section 8, connected with a cylindrical section 9 by way of an annular intervening section 10. This sectional arrangement is utilized to facilitate assembly and repairs. The cap section 8 is provided with an insulation collar 11, and the cylindrical section 45 9 carries a removable retaining rim 12 for an inflammable closure 13. This may be a 50 paper disc, if desired.

Fastened to the center of this inflammable disc by way of a screw or the like 14 is a ball weight 15. Secured to the upper portion of this ball, as shown in Figure 6 is an insulation sleeve 16 fastened by bolts 17 also 55 serving to hold in position a contact plate 18.

Incidentally the casing is of current conducting material and the ball weight is of current conducting material. The insulated 60 neck 16 extends through and beyond the central opening 19 of a metallic partition plate 20. A ground wire 21 is connected with this plate and in turn is connected with a binding post 22, on an insulation disc 23. 65 A line wire 24 is also connected with the binding post 22 and extends out through the collar 11. The complementary circuit wire 25 extends through this collar and is connected at its inner end with a binding post 26 also 70 on the insulation disc 23. There is a connecting wire 27 between the posts 26 and the current conducting bolt 17 on the ball weight.

The device may be used in a vertical hanging position, as shown in Figure 1.

When the inflammable diaphragm or disc 13 becomes disrupted or burned under the action of flame or heat, it is obvious that the ball 15 will drop down, causing the contact 80 plate 18 to bridge the opening 19 and to close the circuit. Included in the circuit may be an audible bell, a signal light, or other signalling means.

The device is also usable in the horizontal 85 position shown in Figure 4. In the latter position, when the diaphragm 13 becomes disrupted under the action of the flame or heat, the ball will drop down to one side and rest against the casing, thereby grounding the circuit and closing it to illuminate 90 a light or ring a bell.

The structure is also usable in the inverted state as shown in Figure 5. Here when the diaphragm is disrupted, the ball drops 95 downwardly causing the contact plate or strip 18 to bridge the two binding posts 22 and 26, thus closing the circuit in this manner. The variable operation feature of the invention is one to be emphasized, in that it 100

permits the device to be arranged in various places and positions and to operate in a dependable manner to sound an alarm in case of fire.

5 A careful consideration of the description in conjunction with the drawings will enable the reader to obtain a clear understanding of the construction, operation, and features and advantages of the invention.

10 Therefore a more lengthy description is regarded unnecessary.

15 Minor changes in the shape, size, materials, and rearrangement of details coming within the field of invention may be resorted to, in actual practice, if desired.

20 1. A fire alarm switch of the class described comprising a housing, an insulation disc in said housing, a pair of binding posts mounted on said disc, circuit wires connected with said binding posts, a metallic partition in said housing in spaced parallelism to said disc and electrically connected with the housing, a ground wire connected with one of said posts and with said partition, an inflammable element in said housing spaced from said partition, and a relatively movable circuit closing device located in the housing between said partition and said inflammable element and connected with said inflammable element and also electrically connected with the remaining binding post.

25 2. In a fire alarm switch of the class described, a housing, an insulation disc in said housing, binding posts mounted on said disc, circuit wires connected with said binding posts, a partition in said housing having a central aperture, a current conducting wire electrically connecting one of said binding posts with said partition, said partition being in electrical connection with said housing, a replaceable inflammable diaphragm mounted in said housing, a ball like circuit closer normally connected with said diaphragm, electrically connected with the remaining binding post and provided with current conducting and contact means.

30 3. In a fire alarm switch of the class described, a housing constructed of current conducting material, an insulation disc mounted in said housing, binding posts carried by said disc, circuit wires connected with said binding posts, a metallic partition plate in said housing disposed in spaced parallelism to said disc and in electrical connection with said housing and having a central opening formed therein, a current conducting ground wire connecting one of said posts with said partition, a replaceable inflammable diaphragm mounted upon said housing, a weight connected with said diaphragm and located within said housing, said weight including an insulated neck extending through the aperture in said partition and carrying a contact element bridging said aperture, and a current conducting

wire connecting said contact element with the remaining binding post.

In testimony whereof I affix my signature.

GEORGE J. FRANCOEUR.
